UNITED STATES PATENT OFFICE.

AXEL ORLING, OF TOOTING, LONDON, ENGLAND.

APPARATUS FOR REPRODUCING VIBRATIONS OF SMALL AMPLITUDE.

1,094,165.

Specification of Letters Patent.

Patented Apr. 21, 1914.

Application filed July 20, 1912. Serial No. 710,655.

To all whom it may concern:

Be it known that I, AXEL ORLING, a subject of the King of Sweden, residing at No. 222 Seely road, Tooting, in the county of 5 London, England, have invented new and useful Apparatus for Reproducing Vibrations of Small Amplitude, of which the following is a specification.

This invention relates to a new method or 10 means whereby the vibrations of a vibrating body can be reproduced on a scale greatly enlarged (if desired) as compared with the original vibrations. In this specification the word "vibration" is intended and must 15 be taken to include tremor, vibration, shaking and other small or similar displacement or movement. According to this invention, the vibrations, which it is desired to reproduce, are communicated to a stream of fluid 20 in such a way that the said stream is deflected to a greater or less degree from its original path, in consonance with and according to the nature of the vibrations. The words "stream of fluid" as used in this specification are intended and must be taken to 25 include a moving column, jet, and stream of liquid, gas, or other like substance.

In addition to reproducing the vibrations on a large scale, with a minimum of interference 30 with the vibrations of the vibrating body, which vibrations, due to an external operating cause, may be of very feeble force, the invention is such as to be adaptable to cause an electric relay current to traverse 35 a circuit and be rendered available for repeating with enhanced force and amplitude the sequence of the varying vibrations and thereby translate, for example, a message, received in a feeble manner from a long 40 ocean cable, in such a manner which will enable it to be vigorously repeated and forwarded to one or more distant stations. According to some of the methods described, 45 the potential in the relay circuit is caused to vary gradually in value.

If a stream of fluid is penetrated by an element which is adapted to be laterally displaced relatively to the axis of the stream, the branch of the stream which recedes from 50 the section of penetration will, if free to move, undergo an angular deflection relatively to the approaching branch of the stream. In the case of a stream of small section penetrated by a pivotally mounted 55 wire, a transverse vibration of the latter to a degree which is scarcely observable will

cause a marked angular deflection of the receding branch of the stream.

The present invention can be utilized in a variety of ways as will be described with 60 reference to the several figures on the accompanying drawings which illustrate some representative embodiments of the invention.

In these drawings: Figure 1 shows an arrangement whereby the stream of fluid 65 which undergoes angular deflection by the vibrating penetrating element serves directly to complete in alternative directions an electric relay circuit. Figs. 2 and 3 are alternatives to portions of Fig. 1. Fig. 4 70 shows one method whereby the electric potential in the relay circuit may be caused to vary gradually in value in accordance with the angle of deflection of the deviated stream. Fig. 5 shows how the deviated 75 stream method of operation can be adapted to the electrical apparatus hitherto in use to automatically retransmit in a reinforced manner through land lines the feeble electric impulses as they are received through a 80 long submarine cable. Fig. 6 shows how, by a deflected jet of burning gas, an electric current can be invoked in a relay circuit of potential which varies gradually in value 85 in accordance with the angle of deflection of the deviated jet. Fig. 7 is an alternative method of achieving a similar result. Fig. 8 shows a further alternative.

Referring to Fig. 1, *a* is a stream of fluid, *b* is an element on to which the stream *a* is directed and past which it continues to flow in an unbroken stream. If the element *b* is very slightly displaced from the axis of the stream, the receding branch of the stream will be caused to incline relatively to the approaching branch, in the direction of the lateral displacement of the element, and the fluid will impinge on an object at a distance from the central line which is considerable relatively to the amount of the 90 displacement of the element *b* from the axis of the stream. If, as shown in Fig. 1, the element *b* is pivotally mounted and caused to undergo very rapidly recurring angular vibrations of such small amplitude as to be 95 scarcely discernible, a very apparent reproduction of the nature of those vibrations will result.

Suppose for example the element *b* to be secured to a plate which, in an insulated 110 manner, carries two separate metallic surfaces *d* and *e*, of which one is electrically

connected to a wire d^1 and the other to a wire e^1 , which wires serve to support the element in a freely pivoted manner. Suppose also an electro-capillary element f , consisting of two plugs of mercury which protrude from capillary tubes, be so supported that the protruding mercury abuts against the metal surfaces d and e , the inner ends of the plugs of mercury being interconnected by an electrolyte, it will be possible to transmit electric impulses through the capillary element with very high frequency and set up a very rapid oscillation of the element b and obtain a very apparent reproduction of the nature of the oscillations. The deflected stream can be employed to operate an electric relay and cause the electric impulses which originate the vibrations of the element b to be automatically repeated in a reinforced manner through a land line and distant recorder.

Two terminals k^1 k^2 of an electric circuit are so situated as to receive thereon the stream which is composed of electro-conductive fluid, for instance a liquid such as acidulated water, when the stream is deviated from the central position. These terminals are connected to the opposite poles respectively of an electric battery m , the center of the battery being connected to the land line n and earthed at o^1 after traversing a recorder p and any other necessary electrical instrument, the circuit being completed by a lead q from earth o^2 to the stream. The stream serves to complete the electric relay circuit through either k^1 or k^2 when the stream is deviated from its central position, the direction of the current through k^1 being the reverse of that through k^2 .

Fig. 2 shows a modification in which two pairs of terminals r^1 r^2 each consisting of wires so fine as to be unable to support beads of liquid, the circuit being completed through one or the other pair only so long as the deflected liquid streams between the two wires of a pair and bridges the gap between them.

In Fig. 3 the terminals of the relay circuit, instead of being metal, are themselves streams of liquid s^1 s^2 , one or the other of which serves with a portion of the stream a to complete the electric relay circuit through the land lines in one direction or the other, depending on the direction of the deflection of the stream a .

Fig. 4 shows a further alternative method whereby the deflected stream of liquid can be caused to operate an electrical relay. In this arrangement two high resistance wires t^1 t^2 are situated parallel to and in proximity with one another and lie in the direction of the throw of the liquid stream a , when caused to angularly deviate under the influence of the displaceable element b . The

end of one of the wires t^1 are connected to the opposite poles respectively of an electric battery m , the center of the battery being connected to the land line n and earthed at o^1 after traversing a recorder p and any other required electrical instrument, the circuit being completed by a lead q from earth at o^2 to the second high resistance wire t^2 and from t^2 to t^1 through the medium of the interposed conductive liquid of the deflected stream. It is so arranged that the stream, when unaffected by b will impinge at such an adjusted point t^0 that the currents, which tend to flow from the battery in opposite directions through the land line n , will have equal potentials and therefore balance one another. When the stream is deviated to either side of the equilibrium point t^0 , the resistance offered to the flow of the relay electric current in one direction will be increased and in the other direction will be diminished, thus determining a flow of current in the desired direction. With this arrangement the strength of the relay current will increase with the deflection of the stream and the least deflection of the stream will start the current.

Fig. 5 shows how the liquid relay system of the present invention can be applied to existing apparatus to automatically retransmit, in a reinforced manner, electric impulses through land lines. In this the electric impulses from a cable cause angular deviations of a coil u which is suspended within a magnetic field N S in the usual way. The element b , by the lateral displacement of its extremity, causes a deflection of a stream a of liquid, as before described, and directs it to intersect a terminal wire v^1 of a relay circuit or v^2 of an alternative relay circuit the energy for either being derived from a battery w^1 and the circuits completed by a wire x which is continuously intersected by the stream at a very short distance below the point of intersection of either v^1 or v^2 . Each of the last mentioned relay circuits contains an electro-magnet denoted by y^1 and y^2 respectively. If y^1 is energized, a circuit energized by a more powerful source of electricity w^2 will be completed in one direction through a land line z and back through earth or, alternatively, forward through the earth and back through the land line, the construction and arrangement of the switches for reversing the current being of well known character as shown in Fig. 5. To promote the unbroken continuity of the stream of fluid the deflection of the receding branch of which constitutes the foundation of the method of operation of the present invention, a flexible or elastic filament of solid material may be provided to serve as a core or leader. This for example may be a thread, a quartz fiber or may be alternatively a metallic conductor.

Also the stream may be composed of gas or vapor, and this stream may be charged with conductive particles such as finely divided carbon, powdered metal or suspended particles of moisture, with or without a leader of flexible fiber to promote the continuity or conductiveness of the stream.

The stream *a* may consist of ignited combustible gas and the heat of the pencil of flame may be caused to vary the electrical resistance in a conducting wire as illustrated in Fig. 6. In this figure an ignited jet *a* of combustible gas which issues in a fine jet from a supply tube 1 is penetrated by an element *b*, which is so suspended and actuated as to be required to undergo small angular displacements, and in consequence the receding branch 2 of the jet will impinge on a portion 3^1 of a wire 3 which deviates from a central position 3^0 , to the right or left thereof, in accordance with the angular position of the displaceable element *b*.

The extremities 3^2 3^3 of the wire 3 are connected to the terminals of an electric battery 4 whose center is 4^0 . The above mentioned points 3^0 4^0 are interconnected by a circuit which comprises a land line 5 and a recorder 6 for example. If, under such circumstances, the flame impinges at 3^0 the potential in the land line and recorder will be zero but, if the flame deviates from 3^0 it will, by heating the portion of the wire 3 on which it impinges, increase the electrical resistance thereof and permit the battery to energize the recording circuit with a preponderating potential in one direction or the other in accordance with the direction of deviation of the flame from 3^0 .

In Fig. 7 is shown a further alternative method whereby a stream *a*, in the case of liquid, which undergoes fluctuating angular deflection by an oscillating element *b*, is caused to operate in a relay circuit an electric current of potential which varies gradually in value in accordance with the angle of deviation of the deflected stream. In this figure two oppositely directed jets 7 and 8 of electro-conductive liquid delivered in fine streams from the tubes 7^1 and 8^1 respectively, impinge on one another and at the place of meeting the united streams descend in a compound stream 9 to complete communication with a metallic conductor 10. The streams 7 and 8 constitute portions of two opposing branches of an electric circuit which is energized by a battery 4, one terminal of which is by a wire 7^2 connected to the liquid of the jet 7 while the other terminal is connected by a wire 8^2 to the liquid of the jet 8. The center 4^0 of the battery is connected to a land line 5 and thence through a recorder 6 to earth at 11^1 , the circuit being completed by connecting the metallic conductor 10 to earth at 11^2 .

The place of meeting of the two jets of liquid 7, 8 will be determined by the position a^1 of impingement of the deflected stream. If the stream is not deflected and strikes the jets at the central point a^0 , 70 there will be no electric potential in the conductor 10 and therefore no current in the land line 5. If, alternatively, by the displacement of *b* the stream *a* is deflected to a point such as a^1 , on one side of the center 75 a^0 , this will have the effect of lengthening the stream 8 and correspondingly shortening the stream 7, thereby increasing the electric resistance of the former and diminishing that of the latter and so causing an electric current to flow through the land line and recorder in a direction which will depend on the relative situations of a^0 and a^1 .

To avoid interference with steady action by electrolytic generation of gas the terminals 7^2 8^2 are immersed in liquid contained in vertical branches 7^3 8^3 of the tubes 7^1 8^1 . In the upper portions of these branches the gases collect and at intervals are permitted to escape, bubbles of gas being thus prevented from escaping with the streams 7, 8. In various other ways can the potential be gradually varied in value by causing the deflected stream to insert more resistance in one and less resistance in the other of 95 two opposing branches of a relay circuit:— But, by the arrangement of Fig. 8, instead of altering the potential by interposing more or less resistance in two opposing branches of an electric circuit, a 100 greater or less initiating electro-motive force is brought into operation through the medium of the deflection of the deviated stream, the number of cell units of an electric battery which are joined up in series undergoing a variation according to the angle of deflection. According to this figure, a comb of wire teeth carried by a conductor 12 is provided and, between the said teeth, with space intervals, is interposed a plurality of 110 wire terminals each leading from a unit-cell of a battery 4, the said terminals being carried by an insulating support 13.

The center of the battery is connected to earth at 14^1 and the conductor 12 leads to 115 earth at 14^2 through a land line 5 and recorder 6. The stream *a* of liquid on deflection by the oscillating element *b* serves to bridge the space between two consecutive wires carried respectively by the conductor 120 12 and the insulating support 13, the number of unit cells which are thereby introduced in series into the relay circuit being dependent on the angle of deflection of the deviated stream and the direction of the current through the relay circuit depending on the direction of said angle of deflection.

I claim:

1. A relay contrivance comprising a stream of fluid, an element immersed therein, means 130

for causing said element to undergo relative displacement transversely to said stream and relay means operated by the consequent angular displacement of the receding portion 5 of said stream.

2. A relay contrivance comprising a stream of fluid, an element immersed therein, means for causing said element to undergo relative displacement transversely to said stream, a 10 source of electricity and an electric circuit energized by said source and rendered operative by the consequent angular displacement of the receding portion of said stream.

3. A relay contrivance comprising a stream 15 of fluid, an element immersed therein, means

for causing the said element to undergo a series of displacements transversely to the stream, a source of electric energy and opposing circuits energized by said source and alternatively rendered operative by the 20 stream on the transverse displacements of the element.

In testimony whereof I have signed my name to this specification in the presence of two subscribing witnesses.

AXEL ORLING.
